(57) **CLAIM**

The ornamental design for an artificial christmas tree, as shown and described.

DESCRIPTION

FIG. 1 is a front perspective view of an artificial Christmas tree; and,

FIG. 2 is another perspective view thereof, showing the artificial Christmas tree in a decorated state.

The broken lines in FIG. 2 represent environmental subject matter only and form no part of the claimed design.

1 Claim, 2 Drawing Sheets

FIG. 1

FIG. 2
